NATHAN PARRISH, OF KALAMAZOO, MICHIGAN.

Letters Patent No. 72,416, dated December 17, 1867.

IMPROVEMENT IN FAN-BLOWERS.

The Schedule referred to in these Letters Patent and making part of the same.

TO ALL WHOM IT MAY CONCERN:

Be it known that I, NATHAN PARRISH, of Kalamazoo, county of Kalamazoo, and State of Michigan, have invented a new and useful Improvement in Machine or Apparatus for Generating Currents of Air; and I do hereby declare the following to be a full, clear, and exact description of the same, reference being had to the accompanying drawings, making part of this specification, in which—

Figure 1 represents a vertical section of my improved apparatus, taken transversely of the rock-shaft and vibrating or pendulum-fan.

Figure 2 is a vertical section, taken in the line $x x$, fig. 1; and

Figure 3 is a partial section, taken in the line $y y$, fig. 1.

Similar letters of reference denote corresponding parts in all the figures.

The object of my invention is to provide an apparatus, cheap and simple in construction, and not liable to get out of order, by means of which to generate blasts or currents of air, heated or otherwise, for purposes of ventilation, heating, or drying, or wherever artificial currents of air may be made available or useful; and it consists in the employment of a vibrating or pendulum-fan, working in close proximity with the stationary sides and bottom of a triangular case or box, which is provided at its sides with inlet and outlet-valves, arranged and operating as hereinafter described.

To enable others to understand and use my invention, I will proceed to describe the same with reference to the drawings, in which A represents a triangular box or case, made of any desired dimensions to adapt it to the work it is to perform, and of any suitable material, such as tongued-and-grooved boards, or of metal united in such manner as to be rendered air-tight. The bottom, A', is made in the arc of a circle, of which the apex of the triangle, or the centre of the rock-shaft B, supported and vibrating thereon, is the centre, in such manner that the pendulum or fan C, secured to the rock-shaft, and vibrating therewith, shall maintain, at all points in its vibration, a fixed relation to or distance from said bottom, A'. The fan C is made of a size corresponding to the width and depth of case A, so that its edges shall move in close proximity to the sides and bottom thereof, and prevent the passage of air to any considerable extent from one side of the fan to the other. The rock-shaft B is shown notched or recessed to the centre, where it receives the sides of the case, and is provided with set-screws or pivots b, which are so adjusted as to terminate at the centre of motion of the rock-shaft and fan, and rest upon metal plates, secured to the sides of the case in such manner as to form a pivot or knife-edge, upon which the fan and rock-shaft vibrate, thereby avoiding the friction which would be consequent upon the resting of the rock-shaft upon and its rotation in bearings in the case. a a are vertical partitions in case A, extending from the inclined sides to the curved bottom, and forming the ends of the closed portion of said bottom. These sides are provided with two sets of valves, c c' d d', each, the one set, c c', opening inward, and the other, d d', opening outward, of case A. These valves by preference are made double, in the manner represented in fig. 2, being provided with a central bar or partition, e, against which the two flap-doors, hinged on opposite sides of the opening, meet and rest when closed. Underneath the triangular case A is arranged the air-box or receiver D, into which the air is forced from case A, and from which it is conveyed in pipes, or otherwise, to the desired point. Said receiver may be made of any desired form or construction, and extends at its ends up to a point, f, between the inlet and outlet-valves, as shown in figs. 1 and 2, so as to receive the air forced outward from case A through the valves d d'. The bottom of the case A, between the inclined sides and the ends of receiver D, indicated at a² a², is left open, or connected with suitable supply-pipes, through which the supply of air to the inlet-valves c c' is received, and the receiver is perforated at any suitable point or points, as shown at d², to receive discharge-pipes, through which the currents of air generated by the fan C are conveyed to the desired point. E is an upright arm or lever, connected to the rock-shaft B, to the upper end of which is secured a horizontal lever, F, of any suitable length, connected at one end to a pitman, G, and provided at its opposite or short end with a counterpoise to the weight of the long arm and pitman. The object of this arrangement of the levers and counterpoise relative to the rock-shaft and fan, is to enable them to be operated with the smallest practicable expenditure of power. The lower end of pitman G is designed to be connected to a crank, operated by a clock-mechanism, or other suitable driving-power.

The operation will be readily understood.

Motion is imparted to the rock-shaft and pendulum-fan by any suitable mechanism, and, through the arrangement of levers described, the fan is vibrated from side to side in the case, and fitting closely therein, so that the air is prevented from passing, by it, from one side of the case to the other. The inlet-valves upon the opposite sides of the case are alternately opened and closed as the fan recedes from or approaches them, being open as the fan recedes, to supply air to the vacuum which would otherwise be created, and closed to prevent its escape, thereby forcing the air, as the fan again approaches, to escape through the outlet-valves $c c'$ $d d'$, alternately, into the receiver D, whence it is conveyed to the desired point of use.

It will be obvious that the machine or apparatus may be made of any desired size and strength, and may be operated by any suitable power, so that the current or currents of air may be increased or diminished, to adapt it to the purpose for which it is designed to be used.

Having now described my invention, what I claim, and desire to secure by Letters Patent, is—

1. The pendulum-fan C, vibrating, with the rock-shaft B, in close proximity with the stationary sides and bottom of the triangular case A, in combination with the inlet and outlet-valves c and d , arranged and operating substantially as and for the purpose set forth.
2. The triangular case A, provided with the inlet and outlet-valves $c c'$ $d d'$, in combination with the vibrating fan C, rock-shaft B and its operating-levers, and the air-box or receiver D, the whole constructed and arranged in the manner and for the purpose set forth.

NATHAN PARRISH.
